SHEET FEEDING APPARATUS

Leonard Baker, Hillsdale, N. J., and Walter E. Schneider, Pearl River, N. Y., assignors to Dexter Folder Company, Pearl River, N. Y., a corporation of New York

Application September 26, 1945, Serial No. 618,634

4 Claims. (Cl. 271—32)

1

This invention relates to sheet feeding apparatus and more particularly to sheet feeders of the type wherein the sheets are fed one after another from a supply of sheets standing on-edge, as distinguished from feeding such sheets from either the top or bottom of a pile thereof. The sheet feeder of the present invention, while capable of feeding plain sheets of paper, thin cardboard or other relatively flexible material to a printing machine or other instrumentality associated therewith, is particularly adapted for embodiment in signature handling machines, such as, for example, signature gathering and signature insetting machines, for feeding folded sheets, known as "signatures," to mechanisms therein acting on such sheets.

One of the objects of the present invention is to provide a sheet feeder of novel construction and operation whereby sheets or signatures may be effectively separated and withdrawn one after another at high speed from a supply thereof disposed in on-edge position.

Another object of the invention is to provide a novel on-edge feeder so constructed that the supply of sheets or signatures on said feeder may be quickly and easily replenished at the rear thereof, whereby feeding of said sheets or signatures from the front of said supply may continue uninterruptedly and a high output of fed sheets or signatures may be obtained.

Another object is to provide a novel method and means for facilitating withdrawal of sheets or signatures successively from the front of a supply thereof standing on-edge and inclined in a forward direction.

Another object is to provide in a sheet feeder of the above character a novel method and means for materially reducing or substantially eliminating the drag or resistance of the forwardly inclined supply of on-edge sheets or signatures on the foremost sheet or signature upon withdrawal of the latter from said supply.

A further object is to provide in a sheet feeder of the above character novel means for supporting the sheet or signature supply in forwardly inclined position and for conditioning said supply prior to withdrawal of each sheet or signature from the front thereof whereby each sheet or signature is relieved of all drag and resistance thereon to facilitate withdrawal thereof and at the same time prevent displacement of the next or succeeding sheet or signature.

A still further object is to provide suction means of novel construction and operation for separating an edge portion of the foremost sheet

2

or signature from a supply thereof disposed in on-edge position and for moving said portion into position for action thereon of sheet withdrawing means.

5 Another object is to provide novel suction separating means so constructed and operated that proper engagement and accurate separation of the successive sheets or signatures from the supply is assured at high speeds.

10 The above and further objects and novel features of the invention will more fully appear from the following detail description when the same is read in connection with the accompanying drawings. It is to be expressly understood, however, that the drawings are for the purpose of illustration only and are not intended as a definition of the limits of the invention, reference for this latter purpose being had primarily to the appended claims.

In the drawings, wherein like reference characters refer to like parts throughout the several views,

Fig. 1 is a side view of one of the units or sections of a signature insetting machine embodying feeding apparatus constructed and operated in accordance with the present invention, said view being taken looking from the right of Fig. 2 with the near side frame member removed, the transverse shafts and certain parts being shown in section;

Fig. 2 is an end view, looking from the left of Fig. 1, of said unit or section with certain of the parts being omitted and certain other parts having portions thereof broken away for purposes of clearer illustration;

Fig. 3 is a view similar to Fig. 1, but on a larger scale and of the upper part only of said unit or section with parts omitted for purposes of clearer illustration, and showing the supply moving mechanism and control means therefor, and certain parts in the positions they occupy when a sheet or signature is being separated and withdrawn from the supply;

Fig. 4 is a fragmentary top plan view of the supply moving mechanism and control means therefor shown in Fig. 3;

Fig. 5 is an enlarged detail side view, partly in section, of one of the suction sheet or signature separating devices shown in Figs. 1, 2, and 3; and

Fig. 6 is an enlarged detail side view, partly in section, of the valve shown in Figs. 1 and 2 for controlling the operation of the suction sheet or signature separating devices.

55 Referring to the drawings, the novel sheet

feeder of the present invention is herein illustrated, by way of example, as being embodied in one of the units or sections of a multi-unit signature insetting machine wherein sheets that have been previously folded one or more times and known as signatures are automatically and progressively fed from a series of aligned stacks, opened and deposited in open condition one upon another on a saddle-type conveyor for subsequent stitching operations to form a complete book or magazine. The signatures handled in the machine are preferably of the extended lap type to facilitate opening and depositing of the same on the saddle conveyor. For the sake of simplicity and brevity in illustrating and describing the present invention, and since all of the units or sections of the signature insetting machine are identical, only one of said units is shown in the accompanying drawings. It will be understood that the novel sheet feeder may also be embodied in other signature handling machines, such as, flat gathering machines wherein the signatures are gathered one upon another unopened and subsequently stitched together to form a complete book or magazine, or may be employed in association with a printing press or other instrumentality for feeding plain sheets of paper, thin cardboard or other relatively flexible material to said press or instrumentality.

In the particular embodiment of the invention illustrated in the drawings, 10 and 11 indicate plate-like side frame members of the insetting machine unit or section on which are mounted the various parts of said unit including the component parts of the feeder. Frame members 10 and 11 are bolted or otherwise suitably secured to the machine foundation, and are connected together at the top and rear thereof by cross shafts 12, 13 and 14 suitably secured thereto, and at the front thereof by cross shafts 15, 16, 17 and 18 suitably secured thereto.

The various movable parts of the insetting machine unit including the movable parts of the feeder are driven from any suitable source of power (not shown) by a sprocket chain 19 (Fig. 2) which passes around a sprocket 20 fixed on the main drive shaft 21 of the machine. Shaft 21 extends transversely of the machine and is journalled in suitable bearings on the frame members 10, 11. Fixed on shaft 21 and disposed between frame members 10 and 11 is a spur pinion 22 which meshes with an idler spur gear 23 that is journalled on a stud 24 fixed in frame member 11 and projecting inwardly therefrom to receive said idler gear (Figs. 1 and 2). Secured to or formed integrally with gear 23 is a spur pinion 25 which meshes with a spur gear 26 that is fixed on and drives a transversely extending shaft 27 journalled in suitable bearings on frame members 10, 11. Shafts 27 and 31 are disposed in direct vertical alignment and may be termed the lower cylinder and cam shaft and the upper cylinder and cam shaft, respectively. The hereinbefore described gearing is so proportioned that shafts 21 and 31 each will be rotated one-half of a revolution for each cycle of operation of the insetting machine

unit whereby two sheets or signatures will be handled, as hereinafter described, for each complete revolution of said shafts.

The sheets or signatures to be handled are stacked in the feeder one behind another standing on-edge and inclined forwardly or in the feeding direction. Thus, the necessity of providing a rear abutment or pusher for supporting the sheet or signature supply is eliminated, and sheets or signatures may be easily and conveniently added to the rear of said supply to replenish the latter whenever necessary and while sheets or signatures are being fed one after another from the front thereof. When signatures are handled, as in the illustrated embodiment, said signatures are preferably stacked in the feeder with their folded or closed edges at the bottom. As shown, the forwardly inclined supply of on-edge sheets or signatures 32 is supported in a hopper comprising a plurality of transversely spaced bottom slats or fingers 33 (Figs. 1 and 4) which are inclined in the direction of shaft 31 and are adapted to receive and support the on-edge sheets or signatures placed thereon by the operator from a sheet or signature loading box 34 that is suitably supported on frame members 10, 11. In the illustrated embodiment, the angle of inclination of slats 33 is substantially 25° from the horizontal. Slats 33 are adjustably clamped, as by clamping blocks 35, to a transversely extending bar 36 which is disposed at the same angle of inclination as said slats and is bolted at opposite ends thereof to side brackets 37 and 38 that are bolted to the inner surfaces of frame members 10, 11, respectively (Figs. 1, 3, and 4).

Novel means are provided for supporting the supply of on-edge sheets or signatures 32 in forwardly inclined position, said means also acting to condition said supply prior to withdrawal of each sheet or signature from the front thereof whereby each sheet or signature is relieved of the pressure of the supply thereon during withdrawal thereof, thus materially reducing or practically eliminating all the frictional drag or resistance on the foremost sheet or signature so that the latter may be easily withdrawn from said supply and without displacing the next or succeeding sheet or signature. As herein shown, said supply supporting and conditioning means comprise a plurality of vertically extending, transversely spaced members 39, four being shown, (Figs. 1, 2, and 3) which are arranged at the front of the feeder and disposed substantially at right angles to slats 33. Members 39 which may be conveniently referred to as the sheet or signature supply front abutments and pushers, are of a length such that they extend a short distance above the maximum size sheet or signature to be handled in the feeder, and downwardly for a major portion of the length of said sheet or signature, leaving a small space between the lower ends thereof and slats 33 so that the lower marginal edge portion of each successive front sheet or signature may be separated from the supply by suction separating devices to be hereinafter described. Although four pushers 39 are preferably provided, it will be understood that this number may be varied as desired, and that the intermediate pushers may be eliminated by bridging the two outer pushers with one or more thin plates of the proper length and securing said plates to said outer pushers.

Pushers 39 are engaged over a square cross bar 40 (Figs. 1, 2, and 3) and are held against

displacement from said bar by cover plates 41 that are bolted to said pushers. The latter and parts carried thereby hereinafter described are adjustable along bar 40 and are held in the desired position of adjustment by the clamping action of plates 41. Bar 40 is bolted or otherwise suitably secured at its opposite ends to the free rear ends of a pair of horizontal links 42. Pivotally connected at 43 with links 42 are the lower ends of arms 44 which extend upwardly from said links and are loosely mounted adjacent frame members 10, 11 on a transversely extending rock shaft 45 journalled in suitable bearings on said frame members. Pivotally connected at 46 (Fig. 3) with the forward free end of one of the links 42 is the lower end of a similar arm 47 (Figs. 2 and 3) which extends upwardly from said link in parallel relation with arm 44 and is keyed or otherwise suitably fixed adjacent frame member 11 to a transversely extending rock shaft 48 journalled in suitable bearings on frame members 10, 11. Keyed or otherwise suitably fixed on rock shaft 48 adjacent frame member 10 is a bell crank lever 49 (Figs. 1 and 2) having a rearwardly extending arm 50 and a downwardly extending arm 51, the latter arm being similar to arms 44 and 47 and having its lower free end pivotally connected at 52 with the forward free end of the other link 42. Thus, bar 40 and pushers 39 carried thereby, upon rocking of shaft 48, will have a substantially straight-line reciprocating motion imparted thereto by the described parallelogram system of arms 44, 44, 47, 51 and horizontal links 42, 42.

Pivotally connected at 53 (Figs. 1 and 2) with the free end of arm 50 of bell crank 49 is the upper end of a connecting rod 54 which extends downwardly through the bifurcated end of a stud 55 secured in any suitable manner in the adjacent frame member 10 and projecting inwardly therefrom to receive said rod. The lower end of rod 54 is pivotally connected at 56 with a cam lever 57 that is loosely mounted on the tie shaft 16 adjacent frame member 10. Journalled at 58 on lever 57 is a roller 59 which engages a double cam 60 that is fixed on and rotated by shaft 31 whereby said lever will be rocked once upon each half revolution of said shaft for each cycle of operation of the insetting machine unit. Roller 59 is maintained in engagement with cam 60 by a coil push spring 61 surrounding rod 54 and disposed between stud 55 and a collar 62 adjustably secured on said rod. Lever 57 is thus raised by cam 60 and lowered by spring 61 once during each cycle of operation of the feeder to rotate shaft 48 in opposite directions whereby pushers 39 are moved inwardly by said cam to their full line position shown in Figs. 1 and 3, and then moved outwardly by said spring to their normal dotted line position shown in Fig. 3.

When pushers 39 are moved inwardly as described, pressure is applied rearwardly by said pushers on the front of the supply of on-edge sheets or signatures 32 and consequently the front portion of said supply is compressed, as shown in Figs. 1 and 3, and the foremost sheet or signature of said supply is moved rearwardly a short distance from its normal position. It will be noted that when the front portion of the supply of on-edge sheets or signatures is compressed as aforesaid, no rearward movement will be imparted to the lower marginal edge portions of the sheets or signatures, thus maintaining said portion of the foremost sheet or signature in proper position for action thereon of separating devices to be hereinafter described. When push-

ers 39 are moved outwardly as described, the pressure on the front of the sheet or signature supply is released whereupon the compressed portion of said supply expands and the sheets or signatures return to their original normal position.

The contour of cam 60 is so designed that the aforesaid outward movement of pushers 39 by spring 61 occurs rapidly or with a snap action with the result that the foremost sheet or signature of the supply 32 is momentarily unsupported by the pushers and not pressed against said pushers by the sheets or signatures at the rear thereof. It is during this momentary non-support of the foremost sheet or signature that the latter is withdrawn from the supply as hereinafter described. Thus, upon withdrawal of each foremost sheet or signature from the supply, said sheet or signature is entirely free of the pressure of the supply thereon and is relieved of all drag and resistance of the supply and pushers thereon, thereby greatly facilitating the withdrawal of each foremost sheet or signature from the supply and without displacing the next or succeeding sheet or signature.

Prior to withdrawal of each foremost sheet or signature from the supply 32, a marginal edge portion thereof, i. e. the lower marginal edge portion in the illustrated embodiment, is separated from the supply and moved into position for action thereon of the withdrawing means so that withdrawal of said sheet or signature only and only one sheet or signature at a time from the supply is assured. This separation of the marginal edge portion of the sheet or signature is, in accordance with the present invention, effected by novel suction sheet or signature separating devices four of which are herein shown and carried by the four pushers 39, there being one suction device carried by each pusher. It is to be understood that the number of suction devices employed may be varied as desired. Since the constructions of the four suction sheet or signature separating devices are identical a description of one will suffice for all of the same.

Each suction sheet or signature separating device is preferably constructed, mounted and operated as follows. Pivotally connected at 63 (Fig. 3) with each pusher 39 adjacent the lower end and at opposite sides thereof are corresponding ends of a pair of spaced links 64 (Figs. 1, 2, and 3). Links 64 extend forwardly from each pusher 39 and have their opposite ends pivotally connected at 65 with the upper portion 66 of a sucker housing 67 adjacent the rear end and at opposite sides thereof (Figs. 3 and 5). Housing 67 is provided in the bore 68 thereof with an annular chamber 69 formed by the front and rear ends of two axially spaced bushings 70 and 71. Slidably mounted in bushings 70, 71 and projecting beyond opposite ends of housing 67 is a sucker stem 72 provided with a central bore 73 extending part way therealong and opening outwardly through the rear end thereof. Fixed on the rearwardly projecting end of stem 72 is a rubber suction cup 74 provided with a duct in communication with said cup and with the bore 73 in said stem. Stem 72 is further provided adjacent the closed end of bore 73 therein with a plurality of axially and circumferentially spaced openings 75 whereby communication is established between bore 73 and chamber 69.

Surrounding the rearwardly projecting end of stem 72 and disposed between housing 67 and a collar 76 adjustably secured to said stem, is a light coil spring 77 (Fig. 5) that provides for

yielding movement of stem 72 and suction cup 74 relative to housing 67 when said cup engages the front of the supply of sheets or signatures 32, thereby compensating for variations in the location of the foremost sheet or signature and enabling suction cup 74 to be completely sealed by said sheet or signature without applying any appreciable pressure thereon. Displacement of stem 72 from housing 67 is prevented by a stop-collar 78 adjustably secured to the forwardly projecting end of said stem and adapted to engage the adjacent end of said housing, said collar also serving to control the normal operating position of stem 72 and cup 74, as shown in Fig. 5 so that the openings 75 in said stem are in communication with chamber 69 in housing 67. It will be noted that the openings 75 in stem 72 allow the latter to yield axially an appreciable distance relative to housing 67 without interrupting the communication between chamber 69 and the bore 73 in said stem.

Pivottally connected at 65 with each sucker housing 67 and disposed between links 64 is the lower end of a connecting link 79, the portion 66 of said housing being slotted to receive said link (Figs. 1, 3 and 5). Link 79 extends upwardly from housing 67 and has its upper end pivottally connected at 80 (Fig. 3) with an arm 81 that is keyed or otherwise suitably fixed on rock shaft 45. Pivottally connected at 82 with arm 81 and 45 spaced forwardly of the pivotal connection 80 for link 79, is the upper end of a second link 83 which extends downwardly from said arm and has its lower end pivottally connected at 84 with sucker housing 67 adjacent the forward end thereof. Links 79, 83 of each separating device 67 are guided for vertical movement by a pair of spaced bars 85 which are bolted or otherwise suitably secured to opposite sides of each pusher 39 and extend forwardly therefrom to receive said links.

It will thus appear that by reason of the location of the pivotal connections 80 and 82 in arms 81 at different radial distances from the axis of rotation of shaft 45, the connecting links 83 have imparted thereto a movement of greater extent 45 than that imparted to connecting links 79. Under these conditions, when arms 81 are swung downwardly by shaft 45 from the position shown in Fig. 3, each sucker housing 67 is swung in a counter-clockwise direction (Fig. 3) about pivot 63 by connecting link 79, and counter-clockwise about pivot 65 by connecting link 83. These pivotal movements combined result in swinging of each sucker housing 67 toward the supply of sheets or signatures 32 to engage each suction cup 74 with the lower marginal edge portion of the foremost sheet or signature at spaced points therealong, and in positioning each housing so that each sucker stem 72 is substantially perpendicular to the vertical plane of the supply and the mouth of each suction cup 74 is substantially parallel with the exposed surface of the foremost sheet or signature, as shown in dotted lines in Fig. 3, position B. In this manner, each successive foremost sheet or signature is properly engaged by the suction cups 74 in the position it occupies at the time of such engagement, thereby insuring a perfect seal of said cups on each sheet or signature to effectively grip and accurately separate the same from the supply at high speeds. When arms 81 are swung upwardly to the position shown in Fig. 3, each sucker housing 67 is swung in a clockwise direction (Fig. 3) simultaneously about the spaced pivots 63, 84 to the 75

full line position A, whereupon the lower marginal edge portion of the foremost sheet or signature engaged and gripped by the suction cups 74 is moved away from the supply to a predetermined point and positioned, as shown in dotted lines in Fig. 3, in the path of movement of withdrawing means to be hereinafter described.

Rocking motion is imparted to shaft 45 from shaft 31 to lower and raise arms 81 once during each cycle of operation of the feeder and for this purpose, shaft 31 has fixed thereon adjacent gear 30 a double cam 86 (Figs. 1 and 2) which engages a roller 87 journalled at 88 on a lever 89 that is loosely mounted on tie shaft 16 adjacent frame member 11. Roller 87 is maintained in engagement with cam 86 by a spring-pressed rod 90 which is pivotally connected at 91 with lever 89 and extends upwardly therefrom through a post 92 that is secured in any suitable manner in frame member 11 and projects inwardly therefrom to receive said rod. The spring 93 for rod 90 surrounds the latter between post 92 and a collar 94 adjustably secured on said rod. Pivotally connected at 95 with the free end of lever 89 is the lower end of a connecting rod 96 the upper end of which is pivotally connected at 97 with the free end of an arm 98 (Figs. 1, 2 and 3) that is keyed or otherwise suitably fixed on shaft 45. Lever 89 is thus raised by cam 86 and lowered by spring 93 to rotate shaft 45 in opposite directions whereby sucker housings 67 are swung rearwardly toward the signature supply and positioned as described by said spring, and are swung forwardly away from said supply and positioned as described by said cam.

Suitable valve means are provided for controlling the making and breaking of vacuum at predetermined intervals in the sucker housings 67, sucker stems 72 and suction cups 74, and as herein shown said valve means preferably comprises a valve housing 99 (Figs. 1, 2, and 6) which is bolted or otherwise suitably secured to the inner side of frame member 10. Housing 99 is formed in the bore 100 thereof with three axially and equally spaced annular chambers 101, 102, and 103, and with a relief port 104 communicating with chamber 103 and opening outwardly to atmosphere through opposite sides of said housing (Fig. 6). Connected with housing 99 and communicating with chamber 101 therein is one end of a flexible conduit 105 the opposite end of which is connected with a vacuum pump (not shown) or other suitable source of vacuum. Connected with housing 99 and communicating with chamber 102 therein is one end of a short flexible conduit 106 the opposite end of which is connected with a transversely extending rigid conduit or pipe 107 that is closed at both ends and secured in any suitable manner in frame members 10, 11. Connected with pipe 107 are corresponding ends of a plurality of flexible conduits 108 (Figs. 1 and 5), four in the present instance, the opposite ends of which are connected with the sucker housing 67 and communicate with the chambers 69 in said housings. Suitable pet-cocks or shut-off valves may be disposed between conduit 107 and conduits 108 whereby the amount of vacuum may be varied to suit different grades of stock, and whereby one or more of the suction devices 67 may be rendered imperative at will, such as, the outer suction devices which need not be employed when handling a small size sheet or signature.

Slidably mounted in the bore 100 of valve housing 99 is a valve 109 (Fig. 6) provided intermediate its ends with a reduced portion 110 which is

of a length substantially equal to the overall distance between chambers 101 and 102. Valve 109 projects through opposite ends of housing 89 and pivotally connected at 111 with the rearwardly projecting bifurcated end of said valve is one end of a link 112 the opposite end of which is pivotally connected at 113 with the upper free end of a cam lever 114 (Fig. 1). Lever 114 is pivotally mounted on a stud 115 secured in any suitable manner in frame member 10, and said lever has 10 journalled thereon at 116 a roller 117 which engages a double cam 118 fixed on and rotated by shaft 31. Roller 117 is maintained in engagement with cam 118 by a spring-pressed rod 119 having one end pivotally connected at 120 with lever 114 and the opposite end guided in a suitable opening formed in a post 121 secured in any suitable manner in frame member 10 and projecting inwardly therefrom to receive said rod. The spring 122 for rod 119 encircles the latter between post 121 and a collar 123 adjustably secured on said rod. Valve 109 is thus cam operated in one direction and spring operated in the opposite direction to make and break vacuum in the suction devices 67 once during each cycle of operation of the feeder.

When roller 117 on lever 114 is engaged by the high part of cam 118 as shown in Fig. 1, valve 109 will be in the position shown in full lines in Fig. 6 wherein it will be noted that chamber 101 is in communication with chamber 102 through the reduced portion 110 of said valve and bore 100; and that chamber 103 and relief port 104 are closed to chamber 102 by the large portion of valve 109. Under these conditions vacuum supply conduit 105 will be connected with conduits 106, 107 and, hence, vacuum will be created in suction cups 74 through conduits 108, chambers 89 in sucker housings 67, and openings 75 in sucker stems 72, to cause the sheet or signature engaged by said cups to adhere thereto.

When roller 117 is in the low part of cam 118 upon continued rotation thereof, valve 109 is moved to the broken line position shown in Fig. 6 wherein it will be noted that chamber 103 is placed in communication with chamber 102 through the reduced portion 110 of said valve and bore 100; and that chamber 101 and vacuum supply line 105 are closed to chamber 102 by the large portion of valve 109. Under these conditions, vacuum will be broken in valve housing 39, and the suction cups 74 will be opened to atmosphere through chamber 103 and relief port 104 to cause said cups to release the sheet or signature.

The operations of the pushers 39 and suction devices 67 are so timed relative to each other that said pushers first move inwardly as hereinbefore described to compress the supply of signatures 32. While the front portion of the signature supply is held in compressed condition, the suction devices 67 are swung rearwardly toward the supply, position B, Fig. 3, to engage the suction cups 74 with the lower marginal edge portion of the foremost sheet or signature in the manner hereinbefore described. During this rearward movement of suction devices 67, valve 109 is moved to the full line position shown in Fig. 6 by the described means for this purpose, whereupon vacuum is created in suction cups 74 causing the latter to grip the foremost sheet or signature engaged thereby. Suction devices 67 are then swung forwardly to position A, Fig. 3, as hereinbefore described, while the supply 32 is still being compressed by pushers 39, where-

upon the lower marginal edge portion of the foremost sheet or signature is bent forwardly away from said supply about the lower ends of pushers 39 and brought to a definite angular position, as shown in Fig. 3, for action thereon of withdrawing means to be presently described. Bending of the lower marginal edge portion of the foremost sheet or signature as aforesaid is preferably effected about a pair of anti-friction rollers 124 (Fig. 3) journalled at 125 on opposite sides and adjacent the lower end of each pusher 39, said rollers serving to further facilitate withdrawal of each sheet or signature from the supply.

The separated lower marginal edge portion of the foremost sheet or signature is then gripped by the withdrawing means and simultaneously with said gripping, the pushers 39 are moved rapidly outward as hereinbefore described and the suction cups 74 are released from the sheet or signature by opening said cups to atmosphere through movement of valve 109 to the broken line position shown in Fig. 6, as hereinbefore described, whereupon the foremost sheet or signature released by cups 74 and relieved of the pressure of the supply and all frictional drag and resistance thereon as hereinbefore described is completely withdrawn from the supply by the withdrawing means. The above operations of the pushers 39 and suction devices 67 are repeated in the order described for each successive sheet or signature, whereby the sheets or signatures are rapidly and automatically separated and withdrawn one after another from the front of the supply 32 without interruption so long as said supply is replenished at the rear thereof with additional sheets or signatures and there are sheets or signatures in the hopper.

Any suitable withdrawing means of known design such as, for example, oscillating mechanical gripper-type arms or segments, may be employed for withdrawing the sheets or signatures from the supply 32, but that herein illustrated and preferably employed is in the form of a continuously rotatable mechanical gripper-type cylinder or drum indicated generally at 126 which is fixed on and rotated by shaft 31 and of a diameter so that two sheets or signatures may be withdrawn thereby from the supply 32 upon each complete revolution thereof as well understood in the art. Cylinder 126 is preferably of skeleton construction consisting of two transversely spaced disks 127 (Figs. 1, 2, and 3), each having pivotally mounted thereon at 128 two diametrically opposed grippers 129 which cooperate with gripper pads or seats 130 that are secured to or formed integrally with said disks adjacent the peripheries thereof. Grippers 129 are closed and opened at predetermined intervals as the drum 126 rotates to grip the separated marginal portion of each sheet or signature, completely withdraw the latter from the supply and thereafter release said sheet or signature for further handling thereof. Closing and opening of grippers 129 is effected in known manner by spring and cam actions, respectively, and by known mechanisms which comprise spring-pressed gear segments (not shown) that are pivotally mounted on each disk 127 and mesh with pinions 131 which are secured to or formed integrally with grippers 129, said gear segments being rocked under the control of fixed cams (not shown) surrounding shaft 31 and held against rotation by suitable means supported on frame 10, 11.

Grippers 129 when open are disposed inside the periphery of drum 126, as shown in Figs. 1

11

end 3, and as said drum rotates in the direction of the arrow and a transversely aligned set of open grippers move a short distance beyond withdrawing position, said grippers close against their seats 130, whereupon the previously separated lower marginal edge portion of the foremost sheet or signature is tightly gripped between the grippers and seats at two transversely spaced points and said sheet or signature is completely withdrawn from the supply 32 in a downward and forward direction.

It will be noted that when the lower marginal edge portion of the foremost sheet or signature is separated from the supply 32 by suction devices 67 and the latter are moved to the position A, Fig. 3, in effecting said separation, said portion of the sheet or signature will be positioned substantially tangent to the periphery of drum 126, thus insuring engagement of said sheet or signature by grippers 129. It will also be noted that when pushers 39 are moved outwardly after the lower marginal edge portion of the foremost sheet or signature is separated from the supply, as hereinbefore described, to release the compressed supply and the foremost sheet or signature for extraction therefrom by grippers 129, the suction devices 67 by reason of their connection with said pushers are swung by the latter further outwardly to the position C, Fig. 3, with the result that the suction cups 74 are drawn inside the periphery of drum 126 and clear of each sheet or signature while the latter is extracted from the supply by grippers 129. Thus, suction cups 74 are relieved of any rubbing action thereon by the sheets or signatures during withdrawal thereof which would wear the faces of said cups within a short period and, hence, require frequent replacement of said cups.

In order to maintain each sheet or signature in engagement with drum 126 during downward and forward movement thereof, a plurality of transversely spaced curved guide fingers 132 are provided, said guide fingers being adjustably clamped to a transverse bar 133 which is bolted at its opposite ends to the brackets 37 and 38. Each sheet or signature extracted from supply 32 is carried by grippers 129 and drum 126 to a predetermined point where said grippers are opened and said sheet or signature is released for further handling thereof.

As the sheets or signatures are separated and extracted one after another from the front of the supply 32, the latter is intermittently advanced by mechanism to be presently described which is controlled by novel means so that the front of the supply is maintained at a predetermined position for operation of the separating devices 67 thereon. As shown particularly in Figs. 3 and 4, said supply moving mechanism and control means therefor are preferably constructed, mounted and operated as follows. Extending transversely of the sheet or signature hopper and journalled in suitable bearings in the brackets 37 and 38 is a shaft 134 having keyed or otherwise suitably fixed thereon a plurality of pulleys 135 which project upwardly into the spaces between the bottom fingers 33. Pulleys 135 are suitably grooved to receive the front portions of endless belts 136, preferably V-belts, which extend rearwardly from said pulleys and pass around suitably grooved idler pulleys 137. The latter are journalled at 138 on arms 139 which are adjustably secured to bar 36 by bolts 140 that pass through slots 141 in said arms and are threaded in said bar. Disposed between arms 139 and bar 36

12

36 are blocks 142 which are milled out to straddle said bar and arms and thus hold the latter against swinging movement in a horizontal plane, said blocks being provided with suitable openings to receive bolts 140. By loosening bolts 140 and sliding arms 139 rearwardly relative to blocks 142 and bar 36, belts 136 may be tightened as desired. Belts 136 are so located that the upper reaches thereof are substantially in the same plane or slightly higher than the upper surfaces of fingers 33, and are provided throughout the length thereof with spaced projections or buttons 143 to obtain increased traction on the sheets or signatures and to prevent the rearmost sheets or signatures of the supply from sliding downwardly and rearwardly out of upright position.

During normal operation of the feeder, shaft 134 is operated intermittently to rotate pulleys 135 and belts 136 and advance the supply 32 at suitable intervals in the direction of pushers 39. This intermittent operation of shaft 134 is effected by pawl and ratchet mechanism preferably constructed, mounted and operated as follows. Secured to and rotated by shaft 27 is a double cam 144 (Figs. 1 and 2) which engages a roller 145 journalled at 146 on a lever 147. The latter is pivotally mounted on a stud 148 secured in any suitable manner in frame member 10 and projecting inwardly therefrom to receive said lever. Roller 145 is maintained in engagement with cam 144 by a spring-pressed rod 149 having one end pivotally connected at 150 with lever 147 and the opposite end guided in a suitable opening formed in a post 151 secured in any suitable manner in frame member 10. The spring 152 for rod 149 encircles the latter between post 151 and a collar 153 adjustably secured to said rod.

Pivotally connected at 154 with lever 147 is the lower end of a connecting rod 155 (Figs. 1 and 3) the upper end of which is pivotally connected at 156 with a reciprocated pawl carrier 157 (Figs. 3 and 4). Pawl carrier 157 is loosely mounted for oscillation on the hub 158 of a ratchet 159 which is keyed or otherwise suitably secured to shaft 134 adjacent bracket 37. Pawl carrier 157 has pivoted thereon at 160 a spring-pressed pawl 161 which continuously engages the teeth of ratchet 159. Thus, through oscillation of pawl carrier 157 by cam 144 and spring 152, and engagement of the oscillating pawl 161 with ratchet 159, shaft 134 will be intermittently rotated and thus impart step by step forward movement to belts 136 and supply of sheets or signatures 32.

As the sheets or signatures are fed from the front of the supply 32 by the described separating and withdrawing devices the belts 136 and supply of sheets or signatures are advanced intermittently by the described pawl and ratchet mechanism, and in order to keep the front of the supply at a predetermined position for action thereon of the separating devices 67 the intermittent operation of the pawl and ratchet mechanism is controlled by novel means preferably constructed, mounted and operated as follows. Extending transversely of the sheet or signature hopper at the front thereof and journalled in suitable bearings in brackets 37 and 38 is a shaft 162 having suitably fixed thereon a plurality of transversely spaced fingers 163 (Figs. 3 and 4). These fingers 163 project upwardly from shaft 162 between slats 33 into the path of forward movement of the supply 32 to be engaged by the latter at a plurality of points along the lower transverse edge thereof. When the front of the supply 32 is in proper feeding position, the sheet or

signature contacting surfaces of fingers 163 are disposed substantially in vertical alignment with the contacting surfaces of pushers 39 when the latter are in their normal outward position shown in broken lines in Fig. 3. Fingers 163 yieldingly engage the front of the supply 32 and are urged toward the latter by a light pull spring 164 having one end connected with a small lever 165 secured to shaft 162 and the opposite end connected with a pin 166 secured in a bracket 167. The latter is fixed on a short pin 168 which is secured in any suitable manner in bracket 37 and projects inwardly therefrom to receive bracket 167.

Secured to shaft 162 or formed integrally with lever 165 as shown in Fig. 3 is a downwardly projecting arm 169 which is arranged to engage an abutment in the form of a screw 170 that is adjustably threaded in a lever 171 and locked in adjusted positions by a lock nut 172. Lever 171 is loosely mounted on pin 168 between brackets 37 and 167 and is formed with two angularly related portions 173 and 174 (Fig. 3) that are adapted to engage corresponding sides of bar 133 to limit the extent of pivotal movement of said lever in opposite directions.

Bolted or otherwise suitably secured to lever 171 is at latch 175 (Figs. 3 and 4) which is adapted to normally engage a latch plate 176 that is bolted or otherwise suitably secured to pawl carrier 157 at the side thereof opposite that carrying pawl 161. Latch 175 is biased towards latch plate 176 by a light pull spring 177 having one end connected with a pin 178 (Fig. 4) secured in lever 171 and the opposite end connected with a pin 179 secured in bracket 167. Engagement of latch 175 with plate 176 holds pawl carrier 157 at the end of its power stroke as shown in Fig. 3, thus preventing roller 145 on lever 147 from following the low part of cam 144 and operation of said lever by spring 152 to return said pawl carrier and engage pawl 161 with the next tooth on ratchet 159. Latch 175 is so arranged that it is actually engaged by plate 176 after a slight return movement of pawl carrier 157 so that upon engagement of the high part of cam 144 with roller 145 in each cycle of operation a slight downward movement will be imparted to plate 176 to free latch 175 whereby the latter may easily be moved as hereinafter described to release pawl carrier 157 for return movement.

When the front of the supply of sheets or signatures 32 is at the proper feeding position, the feeler fingers 163 are held by said supply in the position shown in Fig. 3 and, hence, arm 169 is prevented from swinging lever 171 to release latch 175 and enable operation of pawl carrier 157. Thus, no movement will be imparted to feed belts 136 and the supply of sheets or signatures 32 will remain at rest. As sheets or signatures are fed one after another from the front of the supply, the feeler fingers 163 will gradually move rearwardly under the action of spring 164, with a corresponding forward movement of arm 169, so that when a sufficient number of sheets or signatures have been so fed, said arm will swing lever 171 through engagement with abutment 170 against the tension of spring 177 and disengage latch 175 from plate 176. Shaft 134 is then intermittently rotated through engagement of pawl 161 with ratchet 159 and oscillation of the released pawl carrier 157 upon continued rotation of cam 144, thus advancing belts 136 and the supply of sheets or signatures 32 step by step until the front of the supply is at the proper feeding position. As the supply thus ad-

vances, the fingers 163 are moved forwardly by the supply, thus swinging arm 169 rearwardly away from abutment 170. Spring 177 then acts to swing lever 171 rearwardly so that latch 175 is again moved into the path of return movement of pawl carrier 157, thereby preventing further operation of the pawl and ratchet mechanism until advancement of the supply is again necessary at which time said supply will again be advanced as previously described.

When the lower marginal edge portion of the foremost sheet or signature is separated from the supply 32 by the separating devices 67, said portion is drawn past the fingers 163 which yield with the separated portion and then snap back into engagement with the next or succeeding sheet or signature to hold the latter in feeding position and against separating movement with the first sheet or signature. It will be understood that the fingers 163 may, if desired, be cam operated into and out of engagement with the supply 32 in timed relation with the operation of the separating devices 67.

In the illustrated embodiment, each signature extracted from the supply 32 is carried downwardly and forwardly with its closed or folded edge leading by grippers 129 and drum 126 to the low point of said drum and there delivered, when released by said grippers, into a horizontally disposed reversing panel 180 (Figs. 1 and 2) which is supported in any suitable manner on the frame members 10, 11 and provided with a plurality of transversely spaced, longitudinally adjustable signature stops 181. Each signature delivered into panel 180 is moved forwardly therewith by suitable means (not shown) until the closed or folded leading edge thereof engages stops 181, thereby locating the opposite openable edge of said signature in a predetermined position, i. e. substantially at the low point of drum 126, for action thereon of well-known mechanical gripper-type signature transfer means indicated generally at 182.

As shown, the signature transfer means 182 comprise a drum or cylinder in the form of two transversely spaced disks 183 (Figs. 1 and 2) which are secured to and rotated by shaft 27 and are of the same diameter as disks 127 to enable handling of two signatures upon each complete revolution thereof. Pivotedly mounted at 184 on each disk 183 are two diametrically opposed sets of long and short grippers 185 and 186, respectively, which cooperate with gripper pads or seats 187 and 188, respectively, that are secured to or formed integrally with said disk at opposite sides and adjacent the periphery thereof. The long grippers 185 are adapted to grip the entire thickness of each signature, that is both halves thereof, at its openable edge, while the short grippers 186 are adapted to grip only the extended lap or lower half of said signature. Preferably, the seats 187 and 188 for grippers 185 and 186, respectively, are so arranged that each seat 187 is located substantially in alignment with the periphery of its respective disk 183, and each seat 188 is located below the periphery of its respective disk 183, as shown in Fig. 2. In this manner, when the signature is gripped at its openable edge by grippers 185 and 186, the upper or short half of said signature will remain substantially in alignment with the peripheries of disks 183, whereas the lower or lap half of said signature will be bent or deflected downwardly at the 75 gripper location away from the upper half, thus

15

creating a space or gap between the two halves of the signature for reception of signature opening means to be hereinafter described. Closing and opening of grippers 185 and 186 at predetermined intervals and at predetermined points in the path of rotation of disks 183 is effected by suitable mechanisms (not shown) which are similar to the mechanisms hereinbefore described for operating the grippers 129 of the signature withdrawing means 126.

Thus, after each signature is delivered into panel 180 and the folded edge thereof is engaged with stops 181, and while said signature is momentarily at rest in said panel, two transversely aligned long grippers 185 will grip both halves of the signature at the openable edge thereof and two transversely aligned short grippers 186 will grip the lower or lap half only of said signature during rotation of disks 183 in the direction of the arrow (Fig. 1). Accordingly, the signature is drawn from panel 180 in a rearwardly and downwardly direction and with the openable edge thereof now leading.

When disks 183 and grippers 185, 186 have rotated approximately a quarter of a revolution from the signature gripping point at which time the openable edge of the signature gripped by said grippers is located directly above the saddle-type conveyor 189 (Fig. 1), the two transversely aligned long grippers 185 are opened, thus releasing the outer or short half of the signature. Thereupon, as disks 183 continue to rotate and while the inner or lap half of the signature is still gripped by the lap grippers 186 and carried downwardly and forwardly to one side of the saddle conveyor 189, the released outer or short half of said signature travels over and along two transversely spaced, thin, plow-like fingers 190 which have been previously swung upwardly and entered into the spaces between the signature halves created by the lap grippers 186 as previously described.

When the outer or short half of the signature has moved downwardly along fingers 190 a suitable distance to insure proper engagement therewith, said fingers are swung downwardly a suitable distance away from disks 183 and substantially at the same surface speed as the surface speed of downward travel of the signature, thereby diverting the outer or short half of the signature away from the lap half thereof and to the opposite side of the saddle conveyor 189. Thereupon, the fingers 190 are swung rapidly out of engagement with the outer half of the signature, the lap grippers 186 are opened to release the lap half of said signature and the latter drops in opened condition on the saddle conveyor 189. Any suitable means may be provided for holding the signatures in contact with disks 183 during the transfer and opening operations. The above-described signature transfer, opening and depositing operations are repeated for each signature delivered into panel 180.

Fingers 190 which constitute a signature opening device are secured to or formed integrally with arms 191 (Figs. 1 and 2) which are fixed on a transversely extending rock shaft 192. The latter is located directly opposite the shaft 21 and is journaled in suitable bearings in frame members 10, 11. Shaft 192 is rocked at predetermined intervals to swing fingers 190 into and out of signature opening position once during each cycle of operation of the inserting machine unit and in the manner hereinbefore described by a double cam 193 (Fig. 2) which is secured

16

to one side of the idler gear 28 for rotation thereby. Cam 193 engages a roller 194 which is journaled at 195 on the arm 196 of a double armed lever 197 the other arm of which is indicated at 198. Lever 197 is pivotally mounted on a stud 199 which is secured in any suitable manner in the frame member 11 and projects inwardly therefrom to receive said lever. Roller 194 is maintained in engagement with cam 193 by a spring-pressed rod 200 having one end pivotally connected at 201 with arm 198 of lever 197 and the opposite end guided in a suitable opening formed in a post 202 secured in any suitable manner in frame member 11. The spring 203 for rod 200 encircles the latter between post 202 and a collar 204 adjustably secured on said rod. Pivotally connected at 205 with arm 198 of lever 197 is one end of a connecting rod 206 the opposite end of which is pivotally connected at 207 with the free end of an arm 208 that is fixed on shaft 192. Thus, fingers 190 are moved upwardly into signature opening position by cam 193, and are moved downwardly by spring-pressed rod 200 to divert the short half of the signature away from the lap half thereof once during each cycle of operation of the inserting machine unit.

The saddle conveyor 189 is of well-known construction, needing no detail description herein, except to say that its purpose is to advance the signature deposited thereon in open condition one upon another from the various units to a stitching mechanism for binding the assembled signatures together to form a book or magazine.

It will be noted that the sheet feeder of the present invention has been illustrated and described herein with more or less particularity as embodied in a signature handling machine of the inserting type for feeding signatures one after another from the supply to devices in said machine that act to open the successive signatures and deposit them in open condition on a saddle conveyor. While this may be a preferred embodiment of the novel sheet feeder, said feeder is equally adaptable without modification for embodiment in signature handling machines of the flat gathering type for feeding signatures one after another from the supply and depositing the same in flat unopened condition on the trough-like conveyor of said machine; and for association with a printing press or other machine to feed plain unfolded sheets of various materials from the supply to a conveyor or other instrumentality substituted for the reversing panel 180 for presentation thereby to said press or machine.

There is thus provided a novel sheet feeder which is capable of feeding plain or folded sheets at high speed to printing presses, signature handling machines, or other machines acting on such sheets. The forwardly inclined on-edge arrangement of the supply of sheets or signatures eliminates the problem of maintaining a continuous supply of sheets or signatures in the feeder so that feeding of sheets or signatures may continue without interruption for reloading purposes in that the supply is free of any rear supporting means or follower and thus may be replenished with additional sheets or signatures at the rear thereof while sheets or signatures are being fed from the front of the supply. The feeder employs a novel method and means for relieving the foremost sheet or signature of the pressure of the supply and all frictional drag and resistance thereon upon withdrawal thereof, thereby facilitating withdrawal of the successive foremost signatures or sheets and without displacing the

next or succeeding sheet or signature. The feeder also includes suction separating devices of novel construction and operation whereby proper engagement of said devices with a marginal portion of the foremost sheet or signature and accurate separation of said sheet or signature at high speed is always assured, thereby reducing to a minimum or substantially eliminating feeder failures and obtaining a high output of fed sheets or signatures.

Although only a single embodiment of the present invention is herein illustrated and described, it is to be expressly understood that the same is not limited to said embodiment or to the specific type of equipment disclosed. It is also to be expressly understood that, as indicated by the above description, the term "sheet" as herein-after employed is intended to apply to a plain unfolded sheet or to a sheet that is folded one or more times. Various changes may be made in the mechanical details, some of which have been suggested in the foregoing description, and in the design and arrangement of the parts illustrated without departing from the spirit and scope of the invention, as will now be apparent to those skilled in the art. For example, the separating and withdrawing means may be arranged for extraction of the sheets or signatures upwardly out of the hopper, or laterally out of the hopper at either side thereof. Also, auxiliary fixed front abutments may be provided to aid the pushers in supporting the supply of sheets or signatures in forwardly inclined position. For a definition of the limits of the invention reference is had primarily to the appended claims.

What is claimed is:

1. In a sheet feeder having means for supporting a supply of sheets standing on-edge one behind another, the combination of means for separating the lower transverse marginal edge portion of the foremost sheet from the supply and comprising a sucker housing, a stem mounted in said housing for yielding sliding movement relative thereto and extending through one end thereof toward the supply, and a suction cup mounted on the end of said stem, and means to mount and actuate said housing, stem and cup for swinging movement rearwardly and forwardly toward and away from the supply and for swinging movement upwardly and downwardly comprising a transverse rock shaft, an arm fixed on said shaft and extending forwardly therefrom, a pair of links having the upper ends thereof pivotally connected with said arm at different points spaced radially from the axis of said rock shaft and the lower ends thereof pivotally connected with said housing adjacent the front and rear ends thereof, a support, and a link pivotally connected with said support and pivotally connected with the connection adjacent the rear end of said housing for one of said first-named links.

2. Apparatus for feeding sheets in succession from the front of a supply thereof supported in standing edgewise position and inclined forwardly or in the feeding direction, comprising means for withdrawing the foremost sheet from the supply,

and means for relieving the inherent weight of the supply upon said foremost sheet during the withdrawal thereof, said last named means comprising a pair of spaced parallel shafts extending transversely of the supply above the same and spaced forwardly from the front face thereof, parallel levers on said pair of shafts and extending downwardly therefrom, a link pivotally connected to lower end portions of said levers, a transversely extending bar mounted on said link, a plurality of elongated supply engaging pusher members carried by said bar and inclined forwardly from the vertical, cam means for rocking one of said shafts and said levers in one direction prior to withdrawal of the foremost sheet from the supply whereby said pusher members are moved rearwardly and the front portion of the supply is rearwardly displaced thereby, and resilient means under the control of said cam means for rocking the said one shaft and said levers in the opposite direction simultaneously with the withdrawal of the foremost sheet from the supply whereby said pusher members are rapidly moved forwardly away from the rearwardly displaced front portion of the supply.

3. Apparatus as defined in claim 2, wherein said pusher members terminate at their lower ends above the lower edge of the sheet supply, and comprising suction sheet separating devices pivotally mounted on said pusher members for gripping the lower marginal portion of the foremost sheet and bending said portion away from the supply about said pusher ends into position for operative engagement by said withdrawing means, and means for swinging said suction devices toward and away from the supply when said pusher members have been moved rearwardly and the front portion of the supply has been rearwardly displaced thereby.

4. Apparatus as defined in claim 3, comprising rollers rotatably mounted on said pusher members at the lower ends thereof and about the peripheries of which bending of the lower marginal portion of the foremost sheet away from the supply by said suction devices is effected.
